MARKER

Albert J. John, Brookfield, Ill.

Application May 17, 1933, Serial No. 671,499

6 Claims. (Cl. 91—39)

The invention relates to improvements in markers especially adapted for use in marking tennis courts, streets for traffic purposes and the like, the primary object of the invention being 5 the provision of an improved marker of the character indicated which is capable of economical manufacture and highly efficient in use.

Another object of the invention is the provision of an improved construction of the character 10 indicated, equipped with improved means for agitating the liquid used in the marking.

Another object of the invention is the provision of an improved construction of the character indicated so constructed and arranged as to 15 facilitate the following of a straight line in marking.

Another object of the invention is the provision of an improved construction of the character indicated, equipped with improved means for 20 applying the marking liquid to the surface to be marked.

Other objects will appear hereinafter.

The invention consists in the combinations and arrangements of parts hereinafter described and 25 claimed.

The invention will be best understood by reference to the accompanying drawing forming a part of this specification and in which:

Fig. 1 is a side view, shown partially in section, 30 illustrating a marker embodying the invention;

Fig. 2, a top plan view shown partially in horizontal section, corresponding with Fig. 1;

Fig. 3, an enlarged top plan view of the rear portion of a marking trough employed in the 35 construction;

Fig. 4, a side view corresponding with Fig. 3;

Fig. 5, a detail view illustrating an arrangement employed for mounting the marking liquid reservoir on the frame of the apparatus;

Fig. 6, a longitudinal section of a modified form of marking trough; and

Fig. 7, a top plan view corresponding with Fig. 6.

The embodiment of the invention illustrated 45 in the drawing comprises a suitable rectangular frame 10 mounted to travel upon two spaced rear wheels 11 on a transverse axle as shown, and a central front wheel 12. The wheeled frame thus provided is equipped with an operating handle 13 mounted on the rear frame axle and rigidly connected with the frame by means of braces 14. At its upper end the handle 13 is provided with transverse handle bars 15, as shown, and whereby the 50 frame 10 may be readily propelled and manipu-

lated over a flat surface such as a tennis court, paved street, or the like, for marking purposes.

A marking liquid reservoir 16 is removably mounted on the frame 10 and provided with an upwardly swinging lid or cover 17 for supplying 5 the same with a marking liquid. A suitable strainer 18 is provided in the top of the reservoir 16 to strain the liquid supplied.

The front wall 19 of the reservoir 16 is made rearwardly sloping in form as shown, so that the 10 operator may readily view the front wheel 12 and may thus readily cause said front wheel to follow a line in the marking process. The reservoir 16 is made of a size to fit between the side bars of the frame 10. At the four corners of its 15 bottom the reservoir 16 is provided with depending slotted lugs 20 fitting loosely over cross bars or bolts 21 of the frame 10 and whereby the reservoir 16 is conveniently removably mounted on said frame. 20

A rocker shaft 22 is extended across the upper end of the reservoir 16 immediately below the screen 18 and therefore above the normal liquid level in the reservoir. An agitator arm 23 is secured centrally to the rocker shaft 22 and 25 depends, as shown, into the reservoir, being equipped at its lower end with a transverse agitator bar 24. At one side the rocker shaft 22 is provided with a crank arm 25 connected by a link 26 with a crank pin 27 on the corresponding 30 wheel 11 and whereby the agitator bar 24 will be caused to sweep across the bottom of the reservoir 16 in the normal operation of the apparatus, thereby normally keeping the marking liquid in a thoroughly agitated condition. The link 26 is 35 provided with a plurality of holes 28 for adjustable connection with the crank arm 25 and whereby the assembling of the parts is facilitated and an adjustable sweep of the agitator arm 24 obtained. By locating the rocker shaft 22 at the 40 top of the reservoir 16 above the normal level of the liquid therein, any necessity of packing the bearing for said shaft is avoided.

The reservoir 16 is provided at its rear central bottom portion with a discharge spout 29 controlled by a valve 30 which, in turn, is controlled by a rotatable valve rod 31 rotatably mounted on the handle 13 and equipped at its upper end, adjacent the handle bar 15, with an operating handle 32. As indicated, the valve rod 31 is 45 purposely slightly bent so as to exert a normal friction in its upper bearing on the handle bar 15, such normal friction tending to hold said valve rod in adjusted positions and thereby also hold the valve 30 in adjusted positions. By this ar- 50 55

angement, the discharge of the marking liquid from the reservoir 16 may be readily controlled by the operator during normal operations of the apparatus. A marking trough 33 is pivotally mounted adjacent its upper front end, on the rear axle of the frame 10 so as to trail upon the surface over which the apparatus travels. The upper end of the trough 33 is arranged to receive the discharge of the marking liquid from the spout 29 and carries a marking brush 34 at its lower end as shown, said marking brush 34 thus constituting the lower end of said trough and trailing upon the surface to be marked to apply the marking liquid thereto, as will be readily understood. The marking trough is arranged in longitudinal registration with the front wheel 12 so that the line thus made will be applied in longitudinal registration with said wheel, thus greatly facilitating the accurate marking of tennis courts, streets and the like. In order to insure substantially uniform distribution of the marking liquid, longitudinal ribs 35 are formed in the bottom of the trough 33 as shown. To facilitate drainage of the reservoir, the bottom thereof is sloped slightly rearwardly toward the discharge spout.

In the modified trough construction illustrated in Figs. 6 and 7, the brush 34 has been omitted. Otherwise the construction is the same as that already illustrated and described.

While I have illustrated and described the preferred form of construction for carrying my invention into effect, this is capable of variation and modification without departing from the spirit of the invention. I, therefore, do not wish to be limited to the precise details of construction set forth but desire to avail myself of such variations and modifications as come within the scope of the appended claims.

40 I claim:

1. A marker comprising a wheeled frame; a reservoir on said frame; means for depositing material from said reservoir in a line on the surface over which the frame travels; a rocker shaft transversing the upper part of said reservoir; an agitator arm arranged centrally on said shaft and adjustable thereon and depending into said reservoir; a transverse agitator bar at the lower end of said arm; and an adjustable operative connection between said shaft and a wheel of said frame.

2. A marker comprising a wheeled frame having two transverse bars; a reservoir mounted on said frame having slotted members at opposite sides to fit over said bars; and means for depositing material from said reservoir in a line on the surface over which the frame travels.

3. A marker comprising a wheeled frame; a marking trough pivotally mounted to swing free-

ly on said frame under the influence of gravity to trail upon the surface over which said frame travels; a reservoir on said frame; means for discharging liquid from said reservoir into said trough; and a brush arranged with its bristles closing and constituting the lower end of said trough with the tips of said bristles contacting said surface.

4. A marker comprising a wheeled frame; a marking trough pivotally mounted to swing freely on said frame under the influence of gravity to trail upon the surface over which said frame travels; longitudinal distributing ribs on the bottom of said trough; a reservoir on said frame; means for discharging liquid from said reservoir into said trough; and a brush arranged with its bristles closing and constituting the lower end of said trough with the tips of said bristles contacting said surface.

5. A marker comprising a frame having two rear and one intermediate front wheel and two transverse bars; a handle for said frame; a reservoir mounted on said frame and having slotted members at opposite sides to fit over said bars, the front wall of said reservoir being rearwardly sloping to permit a view of said front wheel; a rocker shaft in the upper part of said reservoir; an agitator arm on said shaft depending into said reservoir; a crank arm on said shaft outside said reservoir; a crank pin on a corresponding wheel of said frame; an adjustable link connecting said crank arm and crank pin; a discharge spout for said reservoir; a valve controlling said spout; a rotatable bent valve rod on said handle for controlling said valve; and a marking trough pivotally mounted on said frame to trail upon the surface over which said frame travels and to receive discharge from said spout.

6. A marker comprising a frame having two rear and one intermediate front wheel and two transverse bars; a handle for said frame; a reservoir mounted on said frame and having slotted members at opposite sides to fit over said bars, the front wall of said reservoir being rearwardly sloping to permit a view of said front wheel; a rocker shaft in the upper part of said reservoir; an agitator arm on said shaft depending into said reservoir; a crank arm on said shaft outside said reservoir; a crank pin on a corresponding wheel of said frame; an adjustable link connecting said crank arm and crank pin; a discharge spout for said reservoir; a valve controlling said spout; a rotatable bent valve rod on said handle for controlling said valve; a marking trough pivotally mounted on said frame to trail upon the surface over which said frame travels and to receive discharge from said spout; and a brush detachable on the lower end of said trough.

ALBERT J. JOHN.
